UNITED STATES PATENT OFFICE.

CHARLES C. BADEAU, OF BETHLEHEM, PENNSYLVANIA, ASSIGNOR, BY MESNE ASSIGNMENTS, TO ROLLER-SMITH COMPANY, OF NEW YORK, N. Y., A CORPORATION OF NEW YORK.

CIRCUIT-BREAKER.

993,637.

Specification of Letters Patent. Patented May 30, 1911.

Application filed February 19, 1908. Serial No. 416,765.

To all whom it may concern:

Be it known that I, CHARLES C. BADEAU, a citizen of the United States, residing in Bethlehem, county of Lehigh, State of Pennsylvania, have invented a certain new and useful Circuit-Breaker, of which the following is a specification.

The object I have in view is the production of a circuit breaker, which will be 10 cheaper and simpler than those heretofore employed, and which will avoid the usual secondary contacts. These and further objects will appear from the following specification and accompanying drawings, considered together or separately.

Figure 1 is a side elevation of a circuit breaker embodying my invention. Fig. 2 is a side view of a portion of the main arm and one of the contacts; and Fig. 3 is a section 20 of a modified form of one of the contacts.

In all of the views like parts are designated by the same reference characters.

In carrying out my invention instead of the usual laminated brush forming a main 25 contact, with protecting secondary carbon contacts, I employ a single pair of contacts, which are adapted to carry the current and at the same time take the arc.

In the drawings, 1 is one of the contacts.

30 In the embodiment illustrated it is the movable contact, and is carried upon the main arm 2. This contact is in the form of a cylinder or short rod, and is supported upon the main arm by a bolt 3, which may be a 35 fillister head screw, as shown in Fig. 2, the other end of the screw being set up with a nut, so that the contact will be pinched between the sides of the main arm and good electrical contact secured. To assist in se- 40 curing good contact, I provide copper washers 4-4, on each side of the contact 1, and in actual contact with the two parts of the main arm, all the parts being drawn together and clamped by means of the screw 3.

45 Fig. 3 illustrates a tube 19 which passes through the cylinder from end to end. The bolt 3 passes through this tube. The ends of the tube are spun over against the washers 4-4, clamping the washers against the 50 carbon. The ends of the tube are countersunk in the washers. The contact illustrated in Fig. 3 differs from that shown in Fig. 2 in having rounded edges.

The reason I employ carbon for but one 55 terminal instead of for both is that carbon

is weak mechanically, is hard to mold and is a poor conductor of electricity, therefore with but one contact made of this material only half of the objection is present. The mechanical weakness I reduce to the smallest point by employing the metal center tube and washers, clamping the carbon between the washers and holding it under compression, so that there will be no tensional strains on the carbon, and so that it will resist injury as much as possible. I obviate the difficulty of molding by making the carbon in the form of a short cylinder, which may be "squirted" to shape and made more homogeneous than it may be molded. The 60 hole may be drilled afterward, as described. By rounding off the edges the tendency to break at that place is reduced.

The other contact 5 (in the embodiment illustrated the fixed contact) is formed of a 75 block of cast iron or other crystalline metal. This block is preferably as wide as the contact 1. It is provided with curved notches 6-6 on each side, such notches being curved on a circle of the same diameter as the contact 1. The two notches on the block are preferred so that the block may be turned around after one side of it is burned away, but it is not essential that it be so made. The end of the block is curved at 20, as 80 shown. The block is supported upon a spring 7, which is clamped to the base 8. This spring is of the proper size and shape to carry the current and to press the block 5 against the contact 1 with sufficient pressure 85 to cause proper contact. The spring 7 is clamped between plates 9 and 10, the said plates diverging, as shown, and forming a space for the spring 7 to play between. The plate 9 is so proportioned as to limit the play 90 of the spring to the proper extent, so that the block 5 will be held against the contact 1 with sufficient pressure. The plate 10 is properly formed to limit the outward move- 95 ment of the spring, so as to hold the block in proper position for engagement with the contact 1. The broken line illustrates the position of the block and spring when the circuit breaker is open. The block 5 is se- 100 cured to the spring 7 by means of a screw 18 which enters a tapped opening in the block. A second opening may be arranged on the other side of the block so that the block may be reversed. The main arm 2 may be moved by any suitable means, that 105 110

illustrated being the same as illustrated in my co-pending application for patent, Serial No. 335,057, filed September 18, 1906. In the structure illustrated the main arm is supported upon the main shaft 11, which is carried in the housings 12. The arm is moved by means of a handle lever 13, which carries a roller 14, which is caused to engage with a roller 15 carried by the main arm. The handle lever is actuated by operating a handle 16. The main arm is normally held away from the contact block 5 by means of a conducting ribbon 17, which surrounds the main shaft 11, and has one extremity attached to the main arm and the other to the base, in the manner illustrated in my co-pending application, and also in my Patent No. 747,673, dated December 22, 1903.

20 The spring 7 and plates 9 and 10 are so arranged that the spring is self-aligning; that is to say, as the block 5 moves to follow the carbon contact the notch on the block will be kept in contact with such carbon for a short distance. Then the contact 1 will slide out of the notch 6 upon the curved end 20, striking the arc, the arc tending to fly upward. When the circuit breaker is closed the carbon contact 1 will engage with the block, and preferably in the center of the notch 6, so that all of the surface of the notch will be in contact with the periphery of the carbon, and good electrical contact secured.

30 By means of my improved switch the ordinary secondary carbon contacts are avoided, the main contacts carrying all the current and taking the arc when the circuit is broken. Owing to the shape of the carbon contact 1, it may be turned around when it burns away so that a fresh surface may be presented to the other contact. Instead of carbon, some other material which is either infusible or which goes directly from the solid to the gaseous state on the application of intense heat may be used. As an example of infusible material, or material which goes directly from the solid to the gaseous state on the application of intense heat, there may be silicon or magnetite. Carbon I have successfully used. Instead of cast iron for the contact block 5, any other form of crystalline metal may be employed. In addition to cast iron, as an example of a crystalline metal, may be used cast zinc, some brasses made without tin and alloys of aluminum and zinc, and aluminum, zinc and antimony. I prefer cast iron, however, owing to its cheapness and high melting point. The advantage of crystalline metal for this purpose is that when melted it turns to the globular form and flakes off. Amorphous metals, such as rolled copper, when melted will become hard, and the melted portions 50 adhere tenaciously to the original substance,

55

60

65

thereby presenting a rough surface for engagement with the carbon to the injury of the latter. Owing to the shape of the block 5, it may be reversed and the other side brought into contact with the carbon when the first side becomes burned away.

A further advantage of my invention is that I am enabled to produce a circuit breaker for rough work and for machine shop practice generally for operating motors used in connection with tools. Under such conditions it is necessary to make and break the circuit frequently so as to secure a small movement of the motor. The ordinary circuit breaker with laminated contacts is utterly unsuited for this purpose owing to the arcing across the terminals, which will destroy the laminated structure in a short time. The ordinary rheostat is also unsuited for this purpose, owing to arcing across the segments of the commutator.

It is impossible to use both contacts of carbon, as with such contacts the carrying capacity cannot be obtained that is necessary for commercial conditions. By employing one contact of carbon and the other of metal, the necessary carrying capacity is obtained, and at the same time the wear caused by arcing is cheaply repaired.

In accordance with the provisions of the patent statutes, I have described the principle of my invention, together with the apparatus which I now consider to represent the best embodiment thereof, but I desire to have it understood that the apparatus shown is merely illustrative and that the invention can be carried out in other ways.

Having now described my invention, what I claim as new and desire to secure by Letters Patent is:

1. A circuit breaker having one contact in the form of a yieldingly supported block having a concave portion and a rounded head, and another contact in the form of a cylinder arranged to coöperate first with a rounded head and then with the concave portion of the first mentioned contact when the circuit breaker is closed.

2. A circuit breaker in which the total amount of current is carried by means of two contacts of dissimilar material, one of which contacts being infusible, or that class of material which goes from the solid to the gaseous state on the application of intense heat, and the other contact being formed of a metal which when melted turns to the globular form and flakes off.

3. A circuit breaker in which the total amount of current is carried by means of co-acting contacts of dissimilar material, one of these contacts being of carbon, and the other contact being of a metal which when melted turns to the globular form and flakes off.

4. A circuit breaker in which the total

105

100

105

110

120

125

130

amount of current is carried by co-acting contacts of dissimilar material, one of these contacts being of carbon, and the other contact being of cast iron.

5. A circuit breaker having one contact in the form of a carbon cylinder, and the other in the form of a metal block, the said block having a curved notch on the side which engages with the carbon, the said notch being 10 curved upon a circle of the same diameter as the cylinder.

6. A circuit breaker having one contact in the form of a carbon cylinder, and the other in the form of a metal block, the said 15 metal block having curved notches on each face, and means for supporting the block, the said means permitting removal of the block and reversing it so that the other side can be brought into contact with the carbon.

7. A circuit breaker in which one of the contacts is in the form of a cylindrical block 20 of carbon, having a central tube of metal and washers of metal connected to the tube, the tube being under stress and causing the washers to exert compression upon the carbon. 25

8. A circuit breaker in which one contact is in the form of a cylinder of carbon with a center tube and end washers, the ends of the tube being spun over and in contact with 30 the washers.

This specification signed and witnessed this 14th day of February, 1908.
